UNITED STATES PATENT OFFICE.

PHILLIP H. CORNS, OF DELPHOS, OHIO.

OIL-CAN PUMP.

No. 856,624.

Specification of Letters Patent.

Patented June 11, 1907.

Application filed July 26, 1906. Serial No. 327,837.

To all whom it may concern:

Be it known that I, PHILLIP H. CORNS, a citizen of the United States, residing at Delphos, in the county of Van Wert and State of Ohio, have invented new and useful Improvements in Oil-Can Pumps, of which the following is a specification.

This invention relates to an improvement in oil can pumps designed primarily for pumping oil into lamp fonts and more particularly to that type of pump in which means are provided for automatically preventing the overflow of the lamp font.

The object of the present invention is to provide a simple construction wherein a common pipe serves both as the discharge pipe and the return pipe for the overflow.

A further object of the invention is the provision in a pump of this character a cylinder, a common discharge and return pipe communicating therewith, and a single piston working within the cylinder and alternately effecting the discharge and a return suction through said pipe.

Other objects of the invention will be apparent from the detail description hereinafter when read in connection with the accompanying drawings forming a part hereof, wherein a preferable embodiment of my invention is shown and wherein like numerals of reference refer to similar parts in the several views.

In the drawings, the figure given is a longitudinal section of my improved pump.

Referring now more particularly to the drawing, A designates a cap which is of the usual construction and is adapted to be screwed or otherwise secured in any suitable manner in the top of an oil can. Depending from the cap A is a pump cylinder B, which is provided adjacent its upper end on its interior with a valve seat b, the upper end of said cylinder being normally closed by an outwardly opening valve b' seated on said valve seat. The cylinder B is provided above the valve seat b with a plurality of openings therein b² affording a communication between the interior of the cylinder and the interior of the oil can, for a purpose to be hereinafter more particularly set forth. The lower end of the cylinder B is provided with an inwardly opening check valve b³ of any suitable type, which has a small opening b⁴ formed therein.

C designates the common discharge and return pipe, which is preferably formed in

two telescoping sections, and which extends through the screw cap A and terminates in the usual spout or nozzle c.

D designates a casing which is connected intermediate its ends with the lower end of the common discharge and return pipe C, the upper end of said casing being connected by a pipe d with the pump cylinder B adjacent the upper end thereof and the lower end of said casing being connected by a pipe d' with the pump casing B at some distance from the lower end thereof. Concentrically secured within the casing D so as to form a continuation of the pipe d is a pipe d², the lower end of which terminates short of the lower end of said casing. The upper ends of the pipes d' and d² are normally closed by valves d³ and d⁴, which may be of any ordinary construction.

Working within the pump cylinder B is a solid piston E to which is secured the lower end of a piston rod F, the upper end of which extends through suitable openings in the valve b' and screw cap A and terminates in a suitable operating handle f. The lower portion of the piston rod F is provided with a reduced or flattened portion f' so that for a portion of the stroke of the piston air will be drawn into the interior of the pump cylinder to assist in expelling the oil therefrom.

Having described the construction of my improved pump I will now set forth the operation thereof.

With the piston in its lowermost position, when the same is elevated oil will be drawn through the check valve b³ and into the interior of the pump cylinder B, the valves d³ and d⁴ both being held on their seats so as to cut off communication between the pipes d and d' and the casing D. When the return stroke is started and the piston is moved downwardly, during the first portion of its stroke oil will be delivered through the pipe d' past the valve d⁴ and out through the delivery pipe C and nozzle c. This will continue until the piston passes the lower end of the pipe d', after which the valve d⁴ will be drawn down upon its seat to close the upper end of the pipe d' and the valve d³ will be raised off its seat, the reduced portion f' of the piston rod having by this time passed through the screw cap A, thereby creating a suction through the discharge pipe C and pipes d² and d and returning the overflow to the interior of the pump casing B. During the latter part of the downward

movement of the piston B the oil therebeneath is forced through the reduced opening b^4 in the check valve b^3 back into the oil can. On the next upward stroke of the piston the oil which has been drawn back into the pump casing is lifted beyond the valve b' and is forced out through the openings b^2 into the interior of the oil can. The valve d^3 is so formed that when it is raised off its seat at 10 the upper end of the pipe d^2 , it will not close the lower end of the pipe b . This object is preferably accomplished by forming upon the upper surface of the valve a web or webs, which serve to limit the upward movement thereof, but it is obvious that any other means to limit the upward movement of said valve may be employed.

I do not desire to limit myself to the precise form and construction shown in the 20 drawings, as it is obvious that many minor changes might be made thereto without departing from the spirit of the invention.

I claim:—

1. In an oil can pump, a cylinder, a common 25 discharge and return pipe communicating with the upper and lower portions of said cylinder, and a single piston working within said cylinder and alternately effecting the discharge and a return suction through said pipe.

2. In an oil can pump, a cylinder, a common discharge and return pipe, pipes connecting said discharge and return pipe with the upper and lower portions of said cylinder, 35 valves in said pipes, and a single piston working within said cylinder and alternately effecting the discharge and a return suction through said pipe.

3. In an oil can pump, a cylinder having a reduced opening in the lower end thereof, a common discharge and return pipe, a pipe connecting said discharge and return pipe with the pump cylinder adjacent its upper end, a pipe connecting said discharge and return pipe with said cylinder at some distance from the lower end thereof, valves in 45 said pipes, and a single piston working within said cylinder.

4. In an oil can pump, a cylinder having an inwardly opening valve in the lower end thereof provided with a reduced opening therethrough, a common discharge and return pipe, separate pipes connecting said

common discharge and return pipe with the upper and lower portions of the cylinder, 55 an outwardly opening valve normally closing the upper end of said cylinder, and a single piston working within said cylinder.

5. In an oil can pump, a cylinder having a reduced opening in the lower end thereof, 60 a common discharge and return pipe, a casing communicating with the lower end of the discharge and return pipe, a pipe connecting said casing with the pump cylinder adjacent the upper end thereof, a pipe connecting the 65 casing with the pump cylinder at some distance from the lower end thereof, valves in said pipes, and a single piston working within the cylinder and adapted to alternately actuate said valves to alternately effect a 70 discharge and a return suction through said common discharge and return pipe.

6. In an oil can pump a cylinder, a cap closing the upper end thereof a common discharge and return pipe communicating 75 therewith, a single piston working within said cylinder and alternately effecting the discharge and a return suction through said pipe, and a piston rod connected to said piston and extending through the cap closing the upper end thereof the pump cylinder, the lower end of said piston rod being provided with a reduced portion.

7. In an oil can pump a cylinder having a reduced opening in the lower end thereof and 85 an outwardly opening valve closing the upper end thereof, a common discharge and return pipe, a casing communicating with the lower end of the discharge and return pipe, a pipe connecting said casing with the pump 90 cylinder adjacent the upper end thereof, a pipe concentrically secured within the casing and forming a continuation of the pipe extending to the upper end of the pump cylinder, a pipe connecting the lower end of the 95 casing with the pump cylinder at some distance from the lower end thereof, valves normally closing the upper ends of said two last mentioned pipes, and a single piston working within said pump cylinder.

In testimony whereof I affix my signature, in presence of two subscribing witnesses.

PHILLIP H. CORNS.
